CLAIM

The ornamental design for a television with stand as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a television with stand showing a first embodiment of our new design;

FIG. 2 is a rear view thereof;

FIG. 3 is a right side view thereof;

FIG. 4 is a left side view thereof;

FIG. 5 is a top plan view thereof;

FIG. 6 is a front perspective view thereof;

FIG. 7 is a rear perspective view thereof;

FIG. 8 is a front view of a second embodiment of a television with stand showing the television with stand of FIGS. 1-7 in a different color presentation;

FIG. 9 is a rear view thereof;

FIG. 10 is a right side view thereof;

FIG. 11 is a left side view thereof;

FIG. 12 is a top plan view thereof;

FIG. 13 is a front perspective view thereof;

FIG. 14 is a rear perspective view thereof;

FIG. 15 is a front view of a third embodiment of a television with stand showing the television and stand of FIGS. 1-7 in a different color presentation;

FIG. 16 is a rear view thereof;

FIG. 17 is a right side view thereof;

FIG. 18 is a left side view thereof;

(Continued)

FIG. 19 is a top plan view thereof;
 FIG. 20 is a front perspective view thereof;
 FIG. 21 is a rear perspective view thereof;
 FIG. 22 is a front view of fourth embodiment of a television with stand showing the television with stand of FIGS. 1-7 in a different color presentation;
 FIG. 23 is a rear view thereof;
 FIG. 24 is a right side view thereof;
 FIG. 25 is a left side view thereof;
 FIG. 26 is a top plan view thereof;
 FIG. 27 is a front perspective view thereof; and,
 FIG. 28 is a rear perspective view thereof.
 The broken lines depict portions of the television with stand that form no part of the claimed design.
